UNITED STATES PATENT OFFICE.

WILLY MOOG, OF ARZHEIM, NEAR LANDAU, GERMANY.

APPARATUS AND PROCESS FOR THE PRODUCTION OF COLORED DESIGNS ON LEATHER.

Application filed May 21, 1925. Serial No. 31,965.

To all whom it may concern:

Be it known that I, WILLY Moog, citizen of Germany, residing at Kreuzmuhle, Arzheim, near Landau, Pfalz, Bavaria, Germany, have invented certain new and useful Improvements in Apparatus and Processes for the Production of Colored Designs on Leather, of which the following is a specification.

10 A number of processes are known for enabling colored designs to be produced on leather. Apart from the printing processes of the letterpress printing variety, there is, in particular, a process which consists in 15 covering moistened leather with the face side of an overlay coated with an impression in water-soluble color, and maintaining them under pressure for a short time.

Another process consists in printing the 20 veining or design on leather with fat previous to staining, the leather being then stained in the ordinary way, after which the fat is removed with benzine, or other solvent having a similar action, and finally, the 25 leather is stained again with the same or with a different color. Attempts have been made also to produce colored designs on leather by chemical means, the stainings produced with the aid of ferrous sulphate 30 being discharged partially by using a stencil impregnated with oxalic acid.

These methods, however, have not attained any appreciable importance in the art of coloring leather, partly owing to the 35 cumbersome character of the processes, while on the other hand, some of them, at least, are attended with the defect common to all printing processes, namely, that the applied color covers the background and, consequently, masks more or less completely the 40 special appearance of the leather.

This applies also to a more recent process, in which the leather is polished or roughened uniformly before applying the color design 45 by means of a printing block or stencil, and is smoothed, or otherwise treated mechanically, after the color has been applied.

A special defect of all these processes is 50 that they do not give a fast dyeing that is appropriate to leather, and that the leather so treated loses its characteristic properties.

In order to avoid these defects it is essential, in decorating leather, that the usual 55 leather-staining liquids (solutions of aniline dyes or dyewoods, stains, bleaching agents and the like) should be allowed to act, in

excess, on the leather, for a short time, in the usual way, the surplus color and the like being removed by rinsing after fixation. The processes known hitherto for producing 60 polychrome leather, however, do not admit of such action and subsequent rinsing or washing.

According to this invention, success is attained by applying to the leather—which 65 is spread out on an elastic backing as uniform in character as possible—a stencil the openings in which correspond with the design to be produced. Such a stencil may be replaced by stamps or similar means 70 which, on being pressed on to the leather, cover the latter in such a way as to leave exposed the parts to be stained.

After the stencils or the substitutes therefore have been brought into firm contact 75 with the leather, the liquid dyestuff, stain, or the like is applied to, or poured over, the leather, in excess. The dyestuff is then left to act on the leather until the latter is stained to a sufficient depth, whereupon the 80 superfluous dyestuff or stain is removed, and the leather is washed with a suitable liquid, such as clean water, until all the excess of dyestuff present has been washed away. Preferably the pressure on the stencil or the 85 like is maintained unaltered during the washing process. After the washing liquid has been removed, the stencil is lifted, and the leather is put through the further dressing processes required in the case of various kinds of leather.

Apart from producing staining effects which are pleasing to the eye, this process affords the special advantage that it can be carried out quickly and with the aid of 90 suitable appliances, on a purely manufacturing scale. By means of the process, polychrome designs can be produced on leather by the successive use of stencils of suitable 95 shape and of different colors or shades of color. Similarly the process enables pre-dyed leather to be decorated with parti-colored designs, or color effects to be obtained by discharging, bleaching, etc.

A device suitable for carrying out the 100 process is illustrated, by way of example, in the accompanying drawings, wherein Figure 1 shows the device in side elevation; Figure 2 is a section of same taken at right angles to Figure 1; whilst Figures 3 and 4 110 represent details in sectional elevation and on a larger scale.

Two bearing pedestals *a* and *b* carry a trough *e*, provided with trunnions *c* and *d* and adapted to be rocked by crank mechanism *f* and *g*. The end walls of the trough *e* are elongated upwards and turned inwards to form suitable cavities *e'* in order to prevent the various liquids from splashing out during the rocking step. Bolts *i*, inserted through fillets or the like attached to a supporting bottom *h*, engage in pairs through holes in strong press rails *k* and are provided with butterfly nuts *l*, which latter when tightened, act on means inserted between the rails *k* and the bottom of the trough *e*.

These means consist of a pneumatic pad *m* (Figure 3), the overlying leather *n* to be decorated, a stencil *o*, a wire gauze *p* of fine mesh, a cross-spiral fabric *q* of strong wire, and a cover *r* of hard wood or other suitable material.

The stencil *o* may be replaced, as shown in Figure 4, by a stamp *s*, the figured face of which is pressed against the leather. The cross-spiral fabric *q* may be replaced by any other suitable construction.

The staining liquid and washing agent are fed into the trough *e* through a lateral channel and outlets *t* are provided at the ends of the trough.

After the rails *k* together with the cover *r* have been removed, the strong rubber pneumatic pad *m*—which is left in place in subsequent working—is inflated and laid on the bottom of the trough *e*, as shown in Figure 3, and the leather *n* is laid on said pad, the side to be stained being upwards. The stencil *o* is then laid on, followed by the elastic insets *p* and *q* permitting the passage of the liquid, and finally the cover *r* is placed on top. The pneumatic pad *m* is provided with flanges *m'*, which are pressed tightly against supports by suitable means such as screws, so that none of the liquid can find its way under the pad. The press rails *k* may be secured to the cover *r*.

By placing the butterfly nuts *l* on the bolts *i* and drawing them tight, the stencil *o* is pressed firmly against the leather *n*, so that the subsequently admitted staining and washing liquids cannot penetrate between the stencil *o*, or stamps *s*, and the leather *n*.

The trough *e* is next filled to the required depth with the staining liquid, and the crank mechanism *f* and *g* is set in operation, thereby causing the trough *e* to rock and the staining liquid to flow backwards and forwards. The liquid is retained in the trough due to the upturned cavities *e'*.

After the staining liquid has acted on the leather *n* for a sufficient time, a cock *t* is opened and the escaping staining liquid is replaced by the washing liquid, the mechanism *f* and *g* being set in motion again. Finally, the washing liquid is removed, the

tension means *k* and *l* are loosened and the leather *n* is taken out of the apparatus.

Although the method of using the described device may appear somewhat cumbersome, the pressing of the stencil *o* on to the leather *n* and its removal from the apparatus are really effected very quickly. If, however, it be desired to accelerate these operations, the device can be modified by combining the stencil, the overlying fabrics and cover into an integral unit, adapted to be raised and lowered in a vertical guide, the pressure on the leather being effected, for example, after the manner of a toggle-lever press.

A device equally suitable for carrying out the process comprises a drum on which the leather to be treated is stretched. Thereupon, one or more stencils are placed over the leather and pressed on to it. The drum dips into a trough and is adapted to turn on its horizontal axis. The dyeing or staining liquor or the like is run into the trough, and is afterwards replaced by the washing liquid.

Another embodiment of the device consists of a flat, plane or arched frame, on which the leather is stretched in a vertical or sloping plane. After the stencil or the like has been applied and fixed in position, the dyeing or staining liquor, discharge or the like, is centrifuged, sprayed or otherwise distributed over the leather.

I claim:

1. A process for the production of colored designs on leather which comprises the steps of pressing a stencil tightly against the leather to be decorated; applying a dye-stuff on the exposed portions of the leather; washing the excess dyestuff from the leather; and then relieving the pressure and removing the leather from the stencil.

2. A process for the production of colored designs on leather which comprises the steps of pressing a stencil tightly against the leather to be decorated; applying an excess of dyestuff on the exposed portions of the leather; removing the excess dyestuff from the leather; and then relieving the pressure and removing the leather from the stencil.

3. A device for producing colored designs on leather comprising a trough; a pneumatic pad in said trough and upon which the leather to be decorated is placed, said leather being adapted to have a stencil conforming to the design placed thereon; means for forcing the stencil tightly on said leather; and means for rocking the trough in order that the color shall flow over the entire surface of the stencil and into the openings therein to thus color the exposed portions of the leather.

4. A device for producing colored designs on leather comprising a trough adapted to receive the leather to be decorated; a

- stencil for said leather, said stencil corresponding to the desired design to be produced on the leather; means for forcing the stencil tightly on said leather; and means 5 for rocking the trough in order that the color shall flow over the entire surface of the stencil and into the openings therein to thus color the exposed portions of the leather.
- 10 5. A device for producing colored designs on leather comprising a trough adapted to receive the leather to be decorated; a pattern for said leather; and means for rocking the trough in order that the color shall 15 flow over the entire exposed surfaces of the leather to be stained to thus color the exposed portions of the leather.
6. A device for producing colored designs on leather comprising a trough adapted to receive the leather to be decorated; a stencil for said leather; a plurality of elastic insets adapted to be placed on said stencil; means for forcing the insets and stencil tightly on said leather; and means for rocking the trough in order that the color shall 20 distribute itself through the insets and into the opening in the stencil to thus color the exposed portions of the leather.
- 25 7. A device for producing colored designs on leather comprising a trough adapted to receive the leather to be decorated; a pneumatic pad in said trough and upon which the leather to be decorated is placed; a stencil for said leather; a plurality of elastic insets adapted 30 to be placed on said stencil; means including bolts for forcing the insets and stencil tightly on said leather and on the pneumatic pad; and a crank mechanism adapted to rock the trough in order that the color shall 35 distribute itself through the insets and into the openings in the stencil to thus color the exposed portions of the leather.
- ing the trough in order that the color shall distribute itself through the insets and into the openings in the stencil to thus color the exposed portions of the leather.
8. A device for producing colored designs on leather comprising a pivotally mounted trough adapted to receive the leather to be decorated; a pneumatic pad secured in said trough and upon which the leather to be decorated is placed; a stencil for said leather; a plurality of elastic insets adapted to be placed on said stencil; means for forcing the insets and stencil tightly on said leather; and a crank mechanism adapted to rock the trough in order that the color shall distribute itself through the insets and into the openings in the stencil to thus color the exposed portions of the leather.
9. A device for producing colored designs on leather comprising a pivotally mounted trough adapted to receive the leather to be decorated; a pneumatic pad secured in said trough and upon which the leather to be decorated is placed; a stencil for said leather; a plurality of elastic insets adapted to be placed on said stencil; means including bolts for forcing the insets and stencil tightly on said leather and on the pneumatic pad; and a crank mechanism adapted to rock the trough in order that the color shall distribute itself through the insets and into the openings in the stencil to thus color the exposed portions of the leather.

In testimony whereof I have affixed my signature.

WILLY MOOG.
